UNITED STATES PATENT OFFICE.

JOSEPH LINDBURG, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed December 8, 1923. Serial No. 679,300.

The invention relates to counters or registers, in typewriting machines, for indicating the amount of work done by the operator.

For the purpose of ascertaining the efficiency of the operator, or for ascertaining, without computation or trouble on the part of the operator, the amount of work to be charged for, counters have been provided which register the number of strokes of the space-bar. From this a record of the number of words, and, consequently, of the amount of matter, written, may be obtained; which, however, is more or less inaccurate due to the fact that the space-bar is operated at other times than between words. Heretofore, also, counters have been provided for registering the number of strokes of the character-keys as well as of the space-bar or key; but, in such instances, the carriage, in its letter-feed movement, has been utilized to drive the counter; thus throwing an added and undesirable burden upon the carriage-motor, and causing the counter to register movements and manipulations of the carriage which have no intended relation to the action of the counter.

Furthermore, the use of counters in typewriting machines has heretofore involved special structural features or modifications in the machine, and the counter has often been a more or less permanent feature of the machine, and this, regardless of the fact that the counter, and consequently such special features, are often not desired and merely constitute expensive incumbrances.

Heretofore, moreover, the force of key-stroke or of carriage-motor power, necessary to drive the counter, has been a variable one; being perhaps relatively slight, as, for instance, while units were added in to run the figures of the register up to say 999, but then being much greater, as, for instance, in turning all the wheels together in the movement from 999 to 1000. Such variation in the required force of stroke, when the keys are the impelling power, may be confusing to the operator, resulting in a "miss" in the register, involving error and loss of time for correction, and generally slowing up the operator's work. Where, on the other hand, a fixed motor power, such, for instance, as the spring-drum for driving the carriage, has been relied upon to drive the counter, such motor, if not designed to supply power

which, consequently, is wasted at other times, will be inefficient when called upon at such stated intervals; and "misses", with resultant error and loss of time for correction, may occur. Especially, on these occasions 60 when a particular reading or setting of the number-wheels has called for stronger driving effort, has there been frequent failure of the space-key properly to function on the register. 65

An object of the invention is the provision of means whereby to drive the counter or register from the keys, whether space-key or character-keys, while nevertheless relieving the operator of the effort otherwise involved 70 in running a unit into the register on a single key-stroke. An object of the invention is the provision of means for rendering inconsequential both the added effort involved 75 in driving the counter and any variation in required driving power, due to a particular reading or setting of the number-wheels. In the preferred embodiment of the invention, in which the counter is key-driven, the foregoing objects are attained by means of driving 80 connections, from the key or keys to the register-wheels, so proportioned and geared that several key-strokes are required to run a unit into the register; with the result that the effort required to run in the unit may be distributed until the fraction thereof contributed by a single key-stroke is imperceptible 85 to the operator.

A further object of the invention is the provision of means whereby both character 90 and space key-strokes may be accurately counted; and whereby the carriage may be relieved of the burden of driving the register; and the latter, together with all special connections therefor, be mountable upon, 95 and detachable from, a machine which requires no special structural features for the accommodation and operation of the register, and which may be of the usual standard 100 construction.

A further object of the invention is the provision of means whereby, in and through the operation of the character-keys, the number of words, or amount of matter, written, may be counted into a register uncontrolled by the movements of the carriage; thus eliminating inaccuracies arising from movements and manipulations of the space-key and carriage which have no intended relation to the action of the register. 105 110

Other features and advantages will hereinafter appear.

In the accompanying drawings—

Figure 1 is a sectional side elevation of a typewriting machine, showing a portion of the main frame and carriage thereon and the invention as applied to the machine.

Figure 2 is a top plan view of some of the parts shown in Figure 1.

10 Figure 3 is a perspective view of a shaft to actuate the counter and clutch devices associated therewith.

Figure 4 is a side elevation, as seen from the right-hand side of the machine, of the 15 counter and its supporting bracket.

Figure 5 is a sectional side elevation of a fragment of a typewriting machine, showing the mechanism associated with the type-keys and the space-bar for actuating the 20 counter.

In the Underwood standard typewriting machine, a universal bar 10 is moved rearward, upon the depression of any character-key or of the space bar or key, to actuate 25 an escapement mechanism 7, to permit of a single letter-space movement of the platen-carriage 8 on the main frame 9 of the machine. The universal bar is supported by arms 11 on a rock-shaft 12. A spring 13 holds the universal bar forward in its normal position of rest, and returns the universal bar to such normal position upon release of the character and space keys.

Character-keys 14 are on levers 15, fulcrumed at 16. Springs 17 throw the character-key levers 15 upward to normal position when the character-keys are released. Each character-key lever has a pin-and-slot connection 18 with a bell-crank 19, pivoted 40 at 20 to the frame. An upwardly-extending arm 21 of each of these bell-cranks is pivotally connected at 22 to a type-bar 23, fulcrumed in the usual segment-plate; so that, upon depression of a character-key, the type-bar 45 is thrown upward and rearward to cause the type to strike on the front face of the platen 8. Each type-bar is provided with a shoulder 24 whereby to engage and throw rearward the universal bar for actuation of the escapement mechanism, upon operation 50 of a key.

A space bar or key 25 is supported on arms 26, pivoted at 27 to the frame. An arm 28, which is unitary with the arms 26, 55 extends rearward and upward from the pivot 27, for engagement with an arm 29 fast to the rock-shaft 12, to form a bell-crank with the arms 11 which support the universal bar. Consequently, upon depression of the space bar, the arms 11 are rocked rearward with the universal bar to actuate the escapement mechanism.

The rock-shaft 12, to which the universal bar is connected, is journaled in ears 30^a on the rear of a vertically-disposed standard

30, secured, as by means of bolts 31, to a part 32 of the main frame. Also secured to the rear face of the standard 30, preferably by means of the bolts 31, is a bracket 33 comprising a plate 34 set vertically and in a plane at right angles to the rock-shaft 12. Suitably secured to and supported upon the plate 34 is a bracket having a horizontally-disposed portion 35 and a vertical plate 36 offset upward, parallel to the plate 34. The plate 36 has secured thereto a U shaped bracket 37, to the cross-reach 38 of which a counter or register 39, of any suitable character, is secured.

The number-wheels 40 of the register are 80 driven from a shaft 41, which is journaled in the register-casing, and which projects forward through the bracket-member 38, and carries on its end a worm-gear 42. This gear meshes with a worm 43 on a shaft 44, journaled in the right-hand end portion 45 of the bracket 37. On its left-hand end the shaft 44 carries a clutch-member 46 in engagement with a clutch-member 47 on a stub-shaft 48, journaled in the plate 34. The clutch-member 46 and the left-hand end of the shaft 44 are recessed centrally to receive the right-hand end of the stub-shaft 48; so that the stub-shaft 48 forms one bearing for the shaft 44; the other bearing for the shaft 44 being, as aforesaid, in the right-hand wing of the bracket 37. The shaft 48 passes through the plate 34, and, on the left-hand end thereof, has fast thereto a ratchet-wheel 49. It follows that suitable step-by-step movement of the ratchet-wheel 49 will result in step-by-step movement of the number-wheels of the register.

The ratchet-wheel 49 is moved, through connections now to be described, whenever the rocker, comprising the arms 11 on which the universal bar is supported, is actuated, whether by means of the character-keys or by means of the space-key. To this end, there is loosely pivoted on the ratchet-shaft 48 an arm 50, on which a pawl 51 is pivotally mounted. A spring 52, secured at one end to the pawl 51, and at its other end to a link 53, holds the pawl 51 in engagement with the ratchet 49; so that, when the arm 50 is turned counterclockwise, the ratchet 49 will be given a rotary movement. The link 53 connects the arm 50 to one arm 54 of a lever pivoted at 55 on the bracket-plate 34. A spring 56, connected at one end to the lever-arm 54, and at its other end to the bracket-plate 34, draws the arm 54 rearward and thereby causes an arm 57, which with the arm 54 forms the lever referred to, to be urged forward. A suitable stop 58 may serve to determine the normal position of the lever 54-57 and connected parts. Pivotally supported at its front upon the upper end of the arm 57, and at its rear upon an arm 59, is a link 60. The arm 59 is pivoted at 125

61 to the bracket-plate 34; and the lengths of the arms 59 and 57, and the position of the pivots 55 and 61, are such that a parallel motion of the link 60 is had, which maintains the link horizontal. The link 60, at its rear end, has a pin 60^a fixed thereon against rotary motion. This pin forms the pivotal connection of the lever-arm 57 to the link 60. Fast to the pin 60^a, at the right-hand end thereof, is a block 62, through which block is threaded a screw 63, to be engaged by a boss 64 on the end of one of the arms 11 of the universal-bar rocker.

10 A lock-nut 65 provides for an adjustable setting of the screw 63 in the block 62, so that the movements of the rocker and the lever 54—57 may be properly correlated; and so that, if desired, the throw of the lever 54—57, for a given throw of the universal, may be varied. The mounting of the link 60 is such that, when the rocker is thrown rearward, as a key is depressed, to strike the end of the screw 63, and thereby to actuate the lever-system through which the ratchet 49 receives its rotary movement, there will be little relative up and down movement of the screw 63 on the boss 64, and, consequently, little friction at this point. The cylindrical form of the boss 64 further tends to elimination of friction on contact of the same with the screw 63. A dog or detent 66, pivoted at 67 on the bracket-plate 34, is held against the ratchet 49 by means of a spring 68, to hold the ratchet against accidental rotary displacement, in whatever setting it may have.

15 The lever 54—57 may be of such proportions as to provide for a full one-tooth rotary movement of the ratchet 49 on every stroke of a character-key lever or space-key lever; and the gearing may be such that for a certain number, for example five or ten, of character-key or space-key strokes, one unit will be added into the register. A certain number of key-strokes will be found to be the average number made in the writing and spacing of a word; and the driving connections of the register may be so proportioned that that number of strokes will result in the addition of one unit into the register, so that the register will in such case indicate the number of words written. Whether or not the number of key-strokes required to add one unit into the register be the average number made in the writing of a word, the total number of strokes made, or amount of matter written, will nevertheless be at once deducible from the value, represented in key-strokes, of the units registered.

20 It is to be noted that the power required for running a unit into the register is not derived from a single key-depression, but is contributed fractionally by each of a plurality of key-depressions; thereby so dis-

tributing the required energy as to render almost imperceptible to the operator the effort of driving the register. Even where all the number-wheels may be turned together, as in an advance from the number 79 "999" to the number "1000", the distribution of the required force among a plurality of keys may be such as to make the effort imperceptible to the operator, and not distinguishable from the running in of any other unit. The presence of the register need not be perceptible to the operator; since it demands of him no unusual key-stroke, nor any intermittent variation of key-stroke.

25 Variations may be resorted to within the scope of the invention, and portions of the improvements may be used without others.

Having thus described my invention, I claim:

30 1. A counter operating attachment for a typewriting machine provided with a universal having a slight oscillating movement, said attachment including a support, arms pivoted on the support, a link on said arms having a parallel movement on the support, and a register operably connected with said link, said link being engageable by the universal and relatively arranged with the universal, so that the latter in its operated effective movement will be thrust against the link, whereby the thrust engagement of the universal will operate the register, and said link also having an adjustable member receiving the thrust of said universal.

35 2. A counter operating attachment for a typewriting machine including a universal having a slight oscillating movement, a support, a short and long arm lever on the support, an arm also pivoted on the support, a link connecting said pivotal arm with said lever to have a parallel movement on the support, said link positioned with relation to the universal, so that the latter in its effective movement will be thrust against the link, a register-driving ratchet-wheel, and a driving pawl connected with the long arm of said lever, and a boss adjustable on said link, said support being mounted on the typewriter with the lever approximately at the same angle with said universal, whereby the thrust engagement of the universal with the link and the engagement of the link with the boss will be substantially constant and also its line of thrust.

40 3. A counter operating attachment for a typewriting machine including a universal having a slight oscillating movement, a support, a main lever having short and long arms and fulcrumed on the support, an arm also pivoted on the support, a main link connecting said pivoted arm with the short arm of said lever to have a parallel movement on the support, said main link positioned with relation to the universal, so that

the latter in its effective movement will be thrust against said link, a shaft on the support carrying a ratchet, an arm free on said shaft, a second link connecting the free arm with the long arm of said main lever, a pawl on the pivotal connection of said free arm with said second link, a spring pressing said pawl against said ratchet, whereby swinging of the main lever will advance the ratchet through said pawl, a distance exceeding the stroke of said universal, a boss adjustable on said main link, said support being mounted on the typewriter with the main lever approximately at the same angle with said universal, whereby the place of thrust engagement of the universal against the main link and the boss will be substantially constant and also its line of thrust, and a register actuated from said shaft.

22. 4. The combination with a typewriter having a universal, of a support, a shaft on the support, operable means on the support for intermittently advancing said shaft as the universal is operated, a clutch-member on said shaft comprising a cross-arm and an axial extension beyond the arm, a register on the support, including a second shaft in engagement with the register wheels, a clutch-member on said latter shaft, said clutch-members being at one end of the shaft element and a bearing at the other end beyond its register engagement, a ratchet on said first-mentioned shaft, and link members engaged by the universal to actuate the clutch shafts.

23. 5. The combination with a typewriter having a universal, of a support, a shaft on the support, a clutch-member on said shaft comprising a cross-arm and an axial extension beyond the arm, a register on the support including a second shaft in engagement with

the register-wheels, and a clutch-member on said latter shaft, said clutch-members being at one end of the shaft element and a bearing at the other end beyond its register engagement. 45

6. The combination with a typewriter having a universal, of a support, a shaft on said support, means including links for intermittently advancing said shaft, a thrust-member on said means engaged by the universal to intermittently advance said shaft, a clutch-member on said shaft, a second support detachably connected with said support, a shaft having a bearing member on said second support on one end, the latter shaft having a clutch-member on the other end, which clutch-members are arranged to interengage and to effect the alignment of said shafts, and means on the second shaft for 55 operably engaging a register.

7. An attachment for a typewriting machine having a universal having a slight oscillating movement, said attachment including a support, a main lever fulcrumed 65 on the support, a shaft on the support carrying a ratchet, an arm free on said shaft, a link connecting said arm with said main lever, a pawl on the pivotal connection of said arm with said link, a spring pressing 70 said pawl against said ratchet, whereby swinging of the main lever will advance the ratchet through said pawl, a thrust-receiving member connected with said lever, said support being detachably mounted on the typewriter with the thrust-receiving member arranged to be engaged by the universal, and a register upon said support actuated from said shaft, means being provided for effecting an adjustment of said thrust-receiving 75 member. 80

JOSEPH LINDBURG.
